GAS REGULATOR FOR FIREARMS

John C. Garand, Springfield, Mass.

Application August 3, 1942, Serial No. 453,425

2 Claims. (Cl. 251—35)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a gas regulator for a firearm.

Certain gas-operated firearms have no adjustment for regulating the energy imparted by the actuating gases impinging on the piston. Control of these gases is very desirable because of the fluctuation of the pressures of these gases when using different kinds or lots of ammunition. It is especially desirable to have some regulating means to allow for the escape of excessive high pressure gases and any accumulation of powder residue and carbon attendant with the actuating gases. Ammunition which develops pressures considerably in excess of normal operating pressures produces a violent reaction on the operating mechanism of the firearm which, if continually repeated, may produce breakage of certain components. Powder residue and carbon deposits on the piston and within the cylinder necessitate frequent cleaning of the piston and gas cylinder to maintain proper functioning of the firearm.

Accordingly, it is an object of this invention to provide a method and apparatus for controlling the energy imparted by the actuating gases of gas-operated firearms.

Another object of this invention is to control the energy imparted by the actuating gases of gas-operated firearms by a gas diversion means.

Still another object of this invention is to provide means to substantially eliminate any accumulation of powder residue and carbon within the gas cylinder of a firearm.

A particular object of this invention is to provide gas regulating means for a rifle such as disclosed in U. S. Patent No. 1,892,141 to John C. Garand.

The specific nature of the invention as well as other objects and advantages thereof will clearly appear from a description of a preferred embodiment as shown in the accompanying drawing in which:

Fig. 1 is a longitudinal sectional view of a gas cylinder assembled to a firearm barrel showing the gas cylinder lock screw which embodies this invention secured to the end of the gas cylinder.

Fig. 2 is a longitudinal sectional view of the gas cylinder lock screw as shown in Fig. 1.

Fig. 3 is another longitudinal sectional view of the gas cylinder lock screw as shown in Fig. 1 taken on a plane 3—3 at right angles to the longitudinal sectional view as shown in Fig. 2.

Fig. 4 is a cross sectional view of the gas cylinder lock screw taken along the plane 4—4 of Fig. 2.

Fig. 5 is a cross sectional view of the gas cylinder lock screw taken along the plane 5—5 of Fig. 2.

Fig. 6 is a right end elevational view of the gas cylinder lock screw as shown in Fig. 3.

In Fig. 1 there is shown a gas cylinder screw 1 embodying this invention assembled to the end of a gas cylinder 2 of the type disclosed in U. S. Patent No. 1,892,141 to John C. Garand. The gas cylinder 2 is suitably mounted on a barrel 3 and a cooperating piston 4 is slidably mounted within the gas cylinder 2. A gas port 5 provided in the gas cylinder 2 is in alignment with the gas port 6 provided in the barrel 3. An operating spring 7 is suitably mounted behind the piston 4.

The gas cylinder screw 1 (Fig. 2) comprises a hollow cylindrical body 1a and an integral cylindrical head 1b. A threaded portion 1c is provided on the exterior periphery of the shank end of the lock screw 1 to secure the screw 1 to the gas cylinder 2. An axial threaded hole 9 is provided in the shank end of screw 1. This hole extends inwardly about one-half the length of the lock screw 1. An annular groove 10 is provided at the bottom of the hole 9 for manufacturing convenience to produce a squared bottom surface. Another annular groove 11 is provided approximately in the center of the hole 9. The grooves 10 and 11 are of slightly larger diameter than the threaded hole 9. An axial hole 12 is provided in the lock screw 1 extending from the face of the head 1b into the hole 9. On each side of the hole 12 and connecting therewith there are provided two opposed smaller holes 14 and 15 which pass through the gas cylinder lock screw 1 down through the groove 11.

A set screw 13 having a socket wrench recess 16 in its head is threadably inserted in the hole 9 with the socket recess 16 facing towards the head 1b. The screw 13 is screwed into hole 9 until the end 13a of the screw 13 projects slightly into the space defined by groove 11. A plug 17 is threadably inserted into the front end of hole 9. This plug projects only a very short distance into the groove 11. A longitudinal hole 18 is centrally provided in the plug 17. The end 18a of hole 18 adjacent the groove 11 is conically counterbored. A pin 20 inserted in a suitable hole 19 provided on the edge of hole 9 secures the plug 17 to the screw 1. The surface 11a of plug 17 is ground off flush with the end 1d of the lock screw 1 and is highly polished to prevent the adherence

of carbon. The end 13a of screw 13 and the end 17b of plug 17 are suitably ground so that when the screw 13 is screwed down to meet the plug 17 perfect contact will be made between the two mating surfaces.

By inserting a socket wrench into the socket 16 of the screw 13, the screw 13 may be readily turned downward to contact the surface 17b of the plug 17. In this position the lock screw 1 is in effect a solid member and therefore no gas can escape from the cylinder 2 outwardly through the gas cylinder lock screw 1. However, when the screw 13 is backed off of the surface 17b, a gas passage will then be opened. The gas may now escape from the hole 18 into the recess formed by the groove 11 and then pass out the holes 14 and 15, which as previously mentioned, extend down into the groove 11.

When shooting a firearm with ammunition which develops higher pressure than desired, the rearward movement of the recoiling mechanism of the firearm will be somewhat violent. While not necessarily harmful to the gun the timing of the feed is quite often upset with resultant malfunctions. Therefore, if it is determined that the pressure being developed by the ammunition is excessive with hole 18 blocked by the screw 13, this pressure may be readily reduced by backing off the screw 13 to provide an exhaust passage for the gas through the hole 18 and the holes 14 and 15. Thus when the cartridge is fired, a portion of the actuating gases impinging on the end of piston 4 will be diverted through the hole 18, thereby reducing the full amount of the force that would otherwise impinge on the end of piston 4 when the gas port 18 is closed.

It should be understood that only a small portion of the actuating gases pass out through the gas port 18 when the screw 13 is in the open position and therefore the remaining energy of the actuating gases is still ample to satisfactorily operate the mechanism of the firearm. It may be readily seen that by providing different diameters of the gas port 18, greater or lesser escape of gas may thereby be provided. It is also apparent that any accumulation of powder re-

sidue or carbon within the cylinder will be blown out through the holes 14 and 15 when the gas port 18 is open.

I claim:

5 1. In a gas cylinder for an automatic firearm, a pressure regulating member comprising a plug adapted to be threaded into the interior of the cylinder, said plug having an axial hole extending therethrough, said hole having a threaded counterbored portion in one end, a valve member threaded into the bottom of the counterbored threaded portion of said hole, means in said valve member arranged to receive a tool for rotating said valve member, a second valve member secured in the outer end of the counterbored threaded portion of said hole said second valve member having an axial gas passage therethrough, the adjacent surfaces of said first valve member and said second valve member being constructed and arranged to seal said gas passage by rotation of said first valve member within the counterbored threaded portion of said hole, an annular recess in said plug located adjacent the plane of engagement of the said adjacent surfaces of said first and said second valve members, and an exhaust passage through said plug connecting with said annular recess.

2. In a gas cylinder for an automatic firearm, a pressure regulating member comprising a plug adapted to be threaded into the interior of the cylinder, said plug having an axial hole extending therethrough, a valve member threaded into said hole, and adapted to be rotated therein, a second valve member secured in said hole adjacent the first-named valve member and having an axial gas passage therethrough, the adjacent surfaces of said valve members being constructed and arranged to seal said gas passage by rotation of said first-named valve member, an annular recess in said plug located adjacent the plane of engagement of the said adjacent surfaces of the valve members, and an exhaust passage through said plug connecting with said annular recess.
